UNITED STATES PATENT OFFICE.

REGINALD A. FESSENDEN, OF BRANT ROCK, MASSACHUSETTS, ASSIGNOR TO NATIONAL ELECTRIC SIGNALING COMPANY, OF PITTSBURGH, PENNSYLVANIA, A CORPORATION OF NEW JERSEY.

WIRELESS SIGNALING.

1,022,540.

Specification of Letters Patent. Patented Apr. 9, 1912.

Application filed April 5, 1907. Serial No. 366,528.

To all whom it may concern:

Be it known that I, REGINALD A. FESSENDEN, a citizen of the United States, residing at Brant Rock, in the State of Massachusetts, have invented certain new and useful Improvements in Wireless Signaling, of which the following is a specification.

My invention relates to simultaneous sending and receiving of signals and more particularly to the simultaneous transmission and receipt of telephonic messages, and to multiplex telegraphy and telephony generally. Its primary object is the simultaneous transmission and receipt of one or more telegraphic or telephonic messages at a wireless station, and also the transmission of messages to and from a wireless station over wire lines.

In the accompanying drawing forming a part of this specification the figure shows in diagram a suitable arrangement for carrying out the invention.

In the drawing 1 and 2 at the bottom of the diagram represent wire lines leading to a telegraph office or a telephone central, 3 and 4 represent the magnet coils of telephone relays, and 5 and 6 the transmitter buttons or their equivalents.

7, 8, 9, 10 represent the primaries of the telephone induction coils and 11, 12, 13, 14, the corresponding secondaries.

15 is a resistance to balance resistance of the telephone line 1, 2.

The primaries and secondaries are so wound and connected that signals or speech impulses transmitted by means of the transmitter button 6 are balanced as regards their effect on the magnet coil 3.

16 is a local battery, 17 (at the top) is a source of voltage, preferably a continuous current dynamo, or otherwise may be storage batteries, 18 is an adjustable resistance, 19 is a discharge gap, 20, 23, 24, 25, 26, 27, 28, 29 are variable capacities; 21, 22, 30, 31 are the primaries of the transformers whose secondaries are 32, 33, 34, 35. 37 is an inductance which may be variable, 38 a resistance, 39 an inductance preferably variable and 40 an antenna grounded at 41, and 42 is a variable capacity. These primaries and secondaries are so wound and connected, and the various inductances and capacities so adjusted empirically that on sending by the sending-key 44 (or when this is short

55 circuited by the switch 45, then on talking

or telegraphing by the line 1, 2) it will not affect the receiver 46. This receiver 46 is connected in with what is well known in the art as an interference preventer as shown here, or as illustrated in my former 60 patents such as No. 918,307, of April 13th, 1909, (Fig. 4); 47, 48 being the primaries and 49 and 50 the corresponding secondaries, 51 a capacity and 52 a potentiometer.

The condenser 26, inductance 37 and resistance 38 form what may be called a "phantom antenna", i. e., they appear to absorb energy to the same extent and to the same amount as the antenna 40 and its connections to ground, and to balance it. 70 This arrangement therefore is believed to be somewhat similar in principle to the balancing arrangement shown at the lower part of the figure in connection with the wire lines and above described. 75

In operation, on sending a telegraphic or telephonic current through the line 1, 2, the switch 45 being closed, the telephonic or telegraphic currents actuate the relay 3, 5 and cause signals to be sent out from the 80 antenna 40 without affecting the receiver 46, or only affecting it to a very slight extent. On the other hand electric waves simultaneously received on the antenna 40 actuate the receiver 46 and by the means of the telephonic relay 4, 6, are transmitted back on the line 1, 2. Similarly if the switch 45 be open, a similar result is obtained on telegraphing with the key 44, in which case the operator may listen to signals 85 received or sent by means of the telephone receiver 53.

Where it is desired to simultaneously transmit and receive a number of messages at the same time, different antennæ may be 90 used suspended from the same tower or the same antenna may be used by duplicating the apparatus as shown to the right of figure, corresponding pieces of apparatus being there indicated by corresponding figures 100 with the prime mark added. The sending and receiving circuits on the right of the figure are tuned to a different frequency from that of the circuits on the left-hand side. 105

By means of the apparatus and operation described it is possible to simultaneously send and receive one or more telephonic or telegraphic messages, either directly from the wireless station, or from local stations 110

connected by wires with the wireless station.

I do not limit myself to the specific arrangements herein set forth, as there are many alternative arrangements which may be used which are fully equivalent or which come under the broad invention as claimed. But

Having thus described my invention and 10 illustrated its use, what I claim herein as new and desire to secure by Letters Patent, is the following:

1. In the art of simultaneous transmission and receipt of wireless signals, the method 15 of neutralizing the effect of the local sending circuit at a station, on a local receiving circuit, which consists in operatively connecting a balancing circuit, and the local sending source to the antennæ, adjusting 20 said circuits so as to maintain a difference of approximately zero potential between two points in said circuits when transmitting, and connecting the receiving circuit operatively to the aerial and between said 25 points.

2. In wireless telegraphy, apparatus for receiving signals without interference from signals being simultaneously sent at the same station, comprising an antenna circuit 30 and a second circuit operatively connected thereto, the said circuits being adjusted to create two points in the second circuit located on opposite sides of the connection to the receiving circuit with zero potential between them, so far as concerns the effect of 35 the transmitted impulses, substantially as described.

3. In wireless telegraph apparatus, means 40 for receiving signals, without interference from signals being simultaneously sent out at the same station, comprising an antenna circuit and a second circuit operatively connected thereto and having its electrical constants arranged proportionately to those of 45 the antenna circuit, said two circuits being so adjusted as to create two points in the sending circuit located on opposite sides of the connection to the receiving circuit with

zero potential between them so far as concerns the effect of the impulses being sent. 50

4. Wireless telegraph apparatus, comprising an antenna circuit and a second circuit operatively connected thereto and having its electrical constants arranged proportionately to those of the antenna circuit, and means to adjust said circuit so as to create two points in the sending circuit located on opposite sides of the connection to the receiving circuit with zero potential between them so far as concerns the effect of the impulses being sent, a telephone relay transmitter in operative relation to the source of the transmitted impulses, a line wire and a receiving electromagnetic instrument in operative relation to the line wire. 60 65

5. In wireless telegraphy, means for simultaneously sending and receiving impulses and preventing their disturbing each other, comprising devices for balancing the receiving circuit against impulses sent out 70 on the same antenna, the receiving circuit being connected between two points on the sending circuit which are maintained at zero potential with respect to the impulses sent out, substantially as described. 75

6. In wireless telegraphy, means for preventing mutual disturbances in simultaneously sending and receiving, by dividing the impulses which would affect the receiver, so as to produce opposing effects on the receiving circuit, which comprises a supplementary circuit containing capacity, inductance and resistance proportional to that of the antenna and a receiving circuit connected across the points of junction 80 thereof with the antenna whereby to balance the effects on the receivers, substantially as described. 85

In testimony whereof I have hereunto signed my name in the presence of the sub- 90 scribing witnesses.

REGINALD A. FESSENDEN.
